ISAAC K. SELLERS, OF LYNCH, KENTUCKY

JOINT

Application filed May 9, 1927. Serial No. 190,042.

This invention relates to improvements in joints for use in certain classes of plumbing installations or the like.

The principal object of the invention is to provide for a slip joint connection or union, whereby to greatly facilitate the installation of the usual soil traps of wash basins, kitchen sinks, drinking fountains and other similar plumbing fixtures and more particularly to effect their connection to the usual soil pipe outlets opening through the walls or partitions of buildings for the purpose, in a manner to eliminate the usual and expensive joint wiping operation.

15 A further object of the invention is to provide for a joint of the character mentioned and one which will effect marked saving in time, labor and material in the installation of the same, in comparison to that now required in the heretofore known types of such joints, in a manner to not in any way lower the usual efficiency of such installations.

With the foregoing and other objects and advantages in view, the invention resides in 25 certain new and useful constructions and arrangements of parts as will be hereinafter more fully described, set forth in the appended claims and illustrated in the accompanying drawings, in which:—

30 Figure 1 is a vertical section through an outer wall of a building and showing an embodiment of the invention in its position of use, the latter, together with certain of its associated parts being shown in section,

35 Figure 2 is a view similar to that of Fig. 1, but showing the use of the joint or union in connection with an arrangement of the plumbing installation within a partition wall of a building, and

40 Figure 3 is an enlarged sectional detail of the joint and certain of its associated parts of a plumbing installation.

45 Referring to the drawing wherein similar characters of reference designate corresponding parts throughout the several views thereof, *a* indicates a usual form of soil discharge pipe as positioned within a wall of a building for the connection therewith of a soil tail pipe *b*, leading from a soil trap *c*, of 50 a wash basin or other similar plumbing fix-

ture *d*, all of conventional form and disposed in their usual operative relation one with respect to the other. To admit of the connection of the soil discharge pipe *a* and the trap tail pipe *b*, in a desired manner, a union 1 is normally employed and is passed through an opening in one side of the wall of a building for the purpose.

In carrying out the objects and purposes of the invention, the union 1 is of a suitable length of tubing, of a ductile metal such as lead, and is spread to a larger diameter, as at 2, at its end to be engaged within the open end of the soil discharge pipe *a*, to receive within the bore of the enlarged end portion 65 2, a ferrule 3, preferably of cast iron. This ferrule 3 is intended to strengthen this part of the union against being distorted from its normal shape when a packing 4, preferably of oakum is forced into position within the 70 open end of the soil discharge pipe *a*, and within the enlarged engaged end 2 of the union. To assure of the packing 4 being retained in a leak preventing state, a packing ring 5 is inserted into the open end of the 75 soil discharge pipe *a* and around the union body 1, after the packing 4 has been previously placed in position.

A second ferrule 6, of metal and preferably of brass, is inserted in the bore of the 80 union 1, at the end of the same opposite to the enlarged end portion 2, and is retained in position therein with a portion of its length projecting outwardly therefrom. This projecting portion of the ferrule 6 is 85 threaded as at 7, to receive thereon a slip nut 8, the latter being positioned on the tail pipe *b* prior to its engagement through the ferrule 6 with the union 1, for the purpose. To prevent leakage from around the ferrule 6 and the slip nut 8, a packing, which may be in the form of a rubber gasket 9 is housed within the slip nut 8 and is properly compressed between the same and the opposed end of the ferrule 6 when the slip nut is tightened in place.

In use, when a plumbing system is installed within a building the union will be placed in position in the walls at all points wherever the usual plumbing fixtures, such as the 131

wash basin *d*, are to be installed and with their enlarged end portions 2 connected to the soil discharge pipe *a*, as heretofore explained. Now, when the fixtures are to be connected up to the unions 1, all that the workmen are required to do is to place the slip nuts 8 with the packing or gasket 9 housed within their threaded ends, on the tail pipes *b*, of the soil trap *c* and insert the free ends of the tail pipes into the unions 1 through the ferrule 6 for a proper or required distance when the slip nuts 8 may be engaged with the threaded ends of the ferrule 6 and tightened thereon.

In Fig. 2 of the drawing, the union 1 is shown as having the end portion opposite to the enlarged end portion 2, angularly bent to admit of its installation within the thinner partition walls of a building, but the union is otherwise in every respect similar to that form of the union as hereinbefore described.

In both instances, in the seating of the ferrules 3 and 6 within their respective ends of a union 1, the same are to be sweated into proper and prominent position therein in the well known manner of metal sweating operations. It should be noted that the bore of the ferrule 6 is of a slightly smaller diameter than that of the union 1, so that the inserted end of the tail pipe *b*, of the trap *c*, is maintained free from all possible contact with the wall of the bore of the union, and this is particularly desirable for the purpose of facilitating the installation of the tail pipe *b* without effort or interference, such as might occur should the inserted end of the latter scrape along or bite into the relatively soft metal forming the wall of the union.

Without further description it is thought that the features and advantages of the invention will be readily apparent to those skilled in the art, and it will of course be understood that changes in the form, proportion and minor details of construction may be resorted to, without departing from the spirit of the invention or its scope as claimed.

Having thus fully described the invention what is claimed is:

1. A soil trap slip joint wall outlet connection comprising a union of a ductile metal, a ferrule set in the adjacent end of said union and having a portion projecting therefrom, said ferrule having its bore of a less diameter than that of the bore of said union and its projecting end exteriorly screw threaded, a packing nut engaged on the threaded end of said ferrule, and a wall cap enclosing said packing nut and the exposed end of said union.

2. A soil trap slip joint wall outlet connection comprising a union of a ductile metal, a ferrule set in the adjacent end of said union and having a portion projecting therefrom, said ferrule having an exterior diameter greater than that of the bore of said

union and its interior diameter less than that of the latter, said ferrule also having its projecting portion exteriorly screw threaded, a packing nut engaged on the threaded end of said ferrule, and a wall cap enclosing said packing nut to the exposed end of said union.
